UNITED STATES PATENT OFFICE.

JAMES R. CRAVATH, OF CHICAGO, ILLINOIS.

LANTERN.

1,081,580.

Specification of Letters Patent. Patented Dec. 16, 1913.

Application filed September 24, 1913. Serial No. 791,498.

To all whom it may concern:

Be it known that I, JAMES R. CRAVATH, citizen of the United States, residing at Chicago, in the county of Cook and State of Illinois, have invented certain new and useful Improvements in Lanterns; and I do hereby declare the following to be a full, clear, and exact description of the invention, such as will enable others skilled in the art to which it appertains to make and use the same.

My invention relates to lighting fixtures and more particularly to the type of appliances known as lanterns and used for shielding outdoor lighting units and for distributing the light thereof. In lighting appliances of this class it has been customary in some cases heretofore to provide a reflector over the lamp both for protecting the lamp and for reflecting in useful downward directions the rays of light which would otherwise be wasted in upward directions. It has also been customary in other cases to provide an inclosing globe or bowl disposed below a hood for the purpose of protecting the lamp from the weather and from accidental breakage and for affording an ornamental diffusing inclosure for the lamp. A third method has been to combine a reflector with an inclosing globe by attaching the globe to the reflector, in which case the metal ring or other device securing the globe to the reflector obstructed and wasted considerable light, thereby greatly reducing the effective surface of the reflector. It has not heretofore been feasible to provide both an effective reflecting surface above the lamp and an inclosing globe around the lamp without either making the reflector unduly large and cumbersome or wasting considerable light and losing the effect of a considerable portion of the reflector surface because of the obstruction offered by the band or collar holding the globe below the reflector. This is because the reflecting surface could not closely approach the neck of the lamp bulb but terminated outside of the inclosing globe, or at a considerable distance from the lamp itself.

One object of my invention is to provide a lighting appliance combining a translucent protecting inclosure or globe for the lamp with a reflector extending both inwardly and outwardly of the juncture of the globe with the reflector, so as also to utilize the reflector for redistributing rays which have

heretofore been used very inefficiently owing to their being within the upward angles enclosed by the inner edge of the reflector and the globe holder.

Other objects are to provide simple means for supporting the globe by clamping the same between the reflector against which the upper end of the globe abuts and an annularly disposed member or members engaging the lower end of the globe; to provide means for supporting the said member or members independently of the reflector, and for readily detaching the former to permit access to the interior of the globe or to permit the replacing of the latter; and to provide a simple lighting appliance presenting the classic appearance of an old-fashioned lantern, but permitting the efficient use of a modern illuminant, such as electricity or gas.

I accomplish these objects by a construction shown in the accompanying drawings in which:

Figure —1— is a sectional view of an electric lighting appliance embodying my invention. Fig. —2— is a fragmentary bottom view of the appliance of Fig. —1—. Figs. —3— and —4— show alternative arrangements of the supporting members of my appliance. Fig. —5— is a fragmentary sectional view showing a modified arrangement of the reflector and the portion of the inclosure abutting against the same.

In the embodiment of Fig. —1—, the appliance of my invention has a hood portion 1 equipped with a threaded inlet 2 by which it is attached to a bracket pipe 3, the bore of the said pipe permitting wires to be brought through the same into the interior of the hood 1. Depending from the hood 1 and preferably at some distance above the lower edge or mouth thereof are a plurality of lugs 4 to which clips 5 are secured by screws 6, the said clips 5 supporting the projecting edge portion of a socket 7 for an incandescent lamp 8 depending vertically from the said socket. Positioned horizontally across the mouth of the hood 1 is an annular reflector 9 of enameled steel or other suitable material having a reflecting surface upon its lower face and having a central perforation 10 adapted to permit the base and neck of the lamp 8 to be inserted therethrough from below when the said lamp is secured to the insulating receptacle 7. The perforation 10 is preferably considerably smaller than the largest diameter of the bulb of the lamp.

8, so that the edge of the annular opening will closely approach the adjacent portion of the neck of the lamp. Positioned below the lamp 8 is a translucent inclosure 11 consisting of a glass cylinder closed at its lower end and abutted at its open upper end against the reflector 9 intermediate of the periphery of the latter and the annular perforation therein. The inclosure 11 is supported by an annular member 12 having an inwardly projecting lip portion contracted to a smaller diameter than the said inclosure, the said annular member being supported by bolts 13 threaded into the lugs 4.

15 When the parts are assembled as in Fig. —1—, it will be evident from the lines 14 representing light rays that the reflector 9 will direct the rays of the lamp striking the portion of the reflector radially just outside 20 of the inclosure 11 which in previous forms would have been obstructed by the globe holder ring; also that the rays 15 reaching the portion of the reflector within the said inclosure will likewise be redirected by the 25 reflector. Consequently, the effective area of the reflector will be considerably increased without increasing the diameter thereof. It will also be evident that by unscrewing the bolts 13 the inclosure 11 can 30 readily be removed, replaced or cleaned upon its interior, and that the upright bolts 13 in combination with the annular member 12 extending around the lower edge of the translucent inclosure will produce an appearance 35 imitating the classic design of the old-fashioned oil lanterns as used upon building fronts in Europe during previous centuries, so that the fixture of my invention will combine the classic appearance of the 40 old-fashioned lantern with an efficient use of the modern illuminant. Moreover, the inclosure 11, which may be either of clear or opalescent glass will simultaneously protect the lamp against deposits of dust and 45 against mechanical strains for which the frail lamp bulb would not have adequate strength.

While I have shown the inclosure 11 as having a closed bottom and as supported by 50 an annular member secured to the hood by detachable bolts, I do not wish to be limited to this or other details of the construction herein disclosed, it being evident that the same might be varied in many ways without 55 departing from the spirit of my invention. For example, Fig. —3— shows an alternative arrangement in which the glass inclosure is open at the bottom so as to permit the entrance of a hand for removing the lamp or 60 cleaning the interior of the inclosure, while Fig. —4— shows a construction in which the member engaging the lower edge of the glass inclosure is supported from the reflector itself, and Fig. —5— shows an alternative arrangement having a cushioning member 65

interposed between the abutting portions of the reflector and the inclosure to prevent the entrance of dust at the said juncture.

It will be evident that none of the embodiments which I show have any screw ring, band, or similar fastening member interposed at the juncture of the glass inclosure and the reflector, hence I avoid the wasting of reflecting surface by the width of the fastening member and the shadows cast thereby, being able to use a reflector reaching substantially up to the neck of the lamp bulb and unobstructed over its whole diameter.

I claim as my invention:

1. A lighting appliance including a lamp, a support therefor, a reflector, a translucent inclosure for the lamp open at one end and abutting at its said end against the reflector, the said reflector extending both inwardly and outwardly of the said end of the inclosure, and means for supporting the said inclosure independently of the reflector.

2. A lighting appliance including a lamp, a reflector, a translucent inclosure for the lamp open at one end and abutting at its said open end against the reflector, the said reflector extending both inwardly and outwardly of the said abutting end of the inclosure, and a plurality of supports for the other end of the inclosure, the said supports coacting to support the inclosure independently of the reflector.

3. A lighting appliance including a lamp, a support therefor, a reflector, a translucent inclosure for the lamp abutting at one end against the reflector, the said reflector extending both inwardly and outwardly of the said abutting end of the said inclosure, an annular member engaging the other end of the inclosure, and a plurality of auxiliary members connecting the annular member with the said support, the said auxiliary members coacting with the annular member to support the inclosure and being adjustable to permit the distance between the annular member and the support to be varied to move the inclosure into and out of its said abutting engagement with the reflector.

4. A lighting appliance including a hood, a lamp supported thereby and depending vertically therefrom, a horizontally disposed perforated reflector carried by the hood, the neck of the said lamp projecting through a perforation in the said reflector, a translucent inclosure for the lamp abutting at its upper end against the said reflector intermediate of the periphery of the latter and the said perforation therein, and means carried by the hood for supporting the said inclosure in its said abutting engagement with the reflector.

5. A lighting appliance including a lamp, a socket therefor, a hood covering and supporting the said socket, a reflector carried by the hood and provided with a perforation,

the neck portion of the said lamp projecting through the said perforation and being adjacent to the edge thereof, a substantially cylindrical inclosure for the lamp abutting at its upper end against the reflector intermediate of the said perforation and of the periphery of the reflector, and supporting means carried by the hood for supporting the said inclosure in its said abutting engagement with the reflector, the said supporting means being adjustable to permit the inclosure to be moved into and out of its said abutting engagement with the reflector.

6. A lighting appliance including a socket, a lamp carried thereby and depending vertically therefrom, a support for the socket equipped with a substantially horizontal reflector, the said reflector having a perforation therein larger than the neck por-

tion of the lamp but of smaller diameter 20 than the largest portion of the bulb of the lamp, the neck portion of the said lamp extending through the said perforation in the reflector, a substantially cylindrical translucent inclosure for the lamp open at its upper 25 end and abutting at its said end against the said reflector intermediate of the periphery of the latter and the perforation therein, and supporting members carried by the said support and supporting the said inclosure in its 30 said abutting engagement with the reflector.

In testimony whereof I have signed my name in presence of two subscribing witnesses.
